UNITED STATES PATENT OFFICE.

WILLIAM F. CLARK, OF CORAOPOLIS, PENNSYLVANIA.

SKELP-CHARGING BENCH.

1,071,879.

Specification of Letters Patent.

Patented Sept. 2, 1913.

Application filed December 6, 1912. Serial No. 735,347.

To all whom it may concern:

Be it known that I, WILLIAM F. CLARK, a citizen of the United States, and a resident of Coraopolis, in the county of Allegheny and State of Pennsylvania, have invented a new and useful Improvement in Skelp-Charging Benches, of which the following is a full, clear, and exact description, reference being had to the accompanying drawings, forming part of this specification, in which—

Figure 1 is a plan view of a portion of a bench showing one form of my improvement, and in which I have also shown a portion of a furnace in section. Fig. 2 is a side elevation of the charging bench shown in Fig. 1. Fig. 3 is a sectional view on the line III—III of Fig. 1, and Fig. 4 is a sectional view on the line IV—IV of Fig. 1.

This invention relates to benches for charging into a furnace long thin pieces of skelp, which are comparatively light and which cannot be charged into a furnace by means of ordinary roll tables, as its weight is insufficient to obtain sufficient traction between the rolls and the skelp. When using the ordinary roll tables the skelp is moved into the furnace rather slowly; and when a portion of the skelp engages the hearth of the furnace, there will not be sufficient traction between it and the rolls to overcome the friction on the hearth of the furnace. I overcome this by the use of a bench having a plurality of rolls which ex-

tend slightly above the bottom of the charging trough, with an electromagnet interposed between them and acting to increase the traction between the rolls and the skelp, so that the latter will be immediately moved at a high rate of speed when it engages the rolls, and such speed will be maintained until after the skelp has passed the last roll.

The precise nature of my invention will be best understood by reference to the accompanying drawings which will now be described, it being premised, however, that various changes may be made in the details of construction and general arrangement of the parts, without departing from the spirit and scope of my invention, as defined in the appended claims.

In the drawings, the numeral 2 designates the frame work of the charging bench, which is supported on wheels 3 engaging the tracks 4.

5 designates a rack on the frame 2 on which the skelp 6 to be charged into the furnace 7 is stacked.

Supported on the frame work 2 and at the side of the rack 5 is a charging trough 8. 60 9 indicates charging rolls journaled in bearings on the frame 2 below the trough 8, and extending slightly above the bottom of the trough, the trough being cut away at this portion for the reception of the rolls. 65 In the drawings I have shown two sets of rolls, each set containing three individual rolls. Each of these rolls is provided with a spindle 10, having a bevel gear 11 connected to its end.

70 12 is a longitudinally extending shaft mounted in bearings supported on the frame 2, and 13 are bevel gear wheels connected to the shaft and which mesh with the gear wheels 10, so that all of the rolls 9 will be rotated in the same direction by the shaft 12. Connected to the end of this shaft 12 is a gear wheel 14 which meshes with a pinion 15 on the shaft of a driving motor 16.

75 17—17 designate electromagnets which are 80 mounted between the rolls 9. I have shown two sets of magnets, one for each set of rolls 9, and each of which has two pole pieces 17^a, which extend upwardly between the rolls 9.

18 are sheets of brass or other non-magnetic material connected to the upper faces of the pole pieces 17^a, so that the skelp 6 will not engage the pole pieces when the end thereof passes the rolls 9.

19 designates a motor which is geared in 90 any suitable manner to the shafts 20 of the supporting wheel 3 to move the table along the tracks 4.

95 The charging table is moved to a point in front of the furnace, and one of the pieces of skelp is moved from the rack 5 to the trough 8. As the skelp reaches the trough and engages the rolls 9, the magnets, which receive their energy from any convenient source, will draw the skelp downwardly 100 against the rolls 9, so that it will immediately travel at a high rate of speed toward the opening of the furnace. The speed of the traveling skelp will be rapidly increased until it reaches the speed of the rolls 9; and 105 although the skelp will engage the hearth of the furnace, the frictional engagement will not be sufficient to materially reduce its speed of travel, as it will be held tightly against the surface of the rollers adjacent to 110

the hearth, and sufficient traction will be maintained between it and the rolls to shoot it into the furnace.

I claim:

5. 1. A skelp charging bench, having a longitudinally extending trough for receiving the skelp, and a plurality of transversely extending rollers journaled below the trough and extending above the bottom thereof, together with an electromagnet between said 10 rollers for maintaining traction between the skelp and the rollers; substantially as described.

2. A skelp charging bench, having a longitudinally extending trough for receiving the skelp, a plurality of transverse rollers below the trough and extending above the bottom thereof, an electromagnet between said rollers for holding the skelp in engagement with the rollers, and means for moving the bench in a transverse direction; substantially as described.

3. A skelp charging bench, having a longitudinally extending trough for receiving the skelp, said trough having an opening between its ends, three rollers journaled below said opening, gearing for rotating said roll-

ers, and an electromagnet having two pole-pieces which extend between adjacent rollers; substantially as described.

4. A skelp charging bench, having a frame supported on wheels, a motor connected to said wheels for moving the bench transversely, a trough supported on said bench, there being an opening in said trough, a plurality of rollers journaled on the bench frame below the trough, said rollers projecting upwardly into the opening above the bottom of the trough, a longitudinally extending shaft journaled in the frame, gears 40 on said shaft for rotating the rolls, means for rotating the longitudinal shaft, and electromagnets having pole-pieces extending upwardly between adjacent rollers; substantially as described.

5. A skelp charging bench, having feed rollers, and traction magnets adjacent to said rollers; substantially as described.

In testimony whereof, I have hereunto set my hand.

WILLIAM F. CLARK.
